UNITED STATES PATENT OFFICE.

HENRY ERNEST PARRY, ROBERT WILLIAM THOMSON, AND WILLIAM JAMES FARLEY, OF PERTH, WESTERN AUSTRALIA, AUSTRALIA.

REVERSIBLE ROTARY ENGINE.

SPECIFICATION forming part of Letters Patent No. 790,523, dated May 23, 1905.

Application filed July 29, 1904. Serial No. 218,686.

To all whom it may concern:

Be it known that we, HENRY ERNEST PARRY, ROBERT WILLIAM THOMSON, and WILLIAM JAMES FARLEY, subjects of the King of Great Britain, and residents of Wellington street, Perth, Western Australia, Australia, have invented certain new and useful Improvements in Reversible Rotary Engines; and we do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention of an improved reversible rotary engine consists in the employment of a rotary and circular piston working within an elliptical-shaped cylinder and also in the peculiar arrangement of a central circular valve which proceeds into the bore of the piston and communicating with ports formed radially in the piston for the admission and exit of steam to and from each of the driving-blades of the piston.

The invention further essentially consists in the means for independently or concurrently operating the valves and also in means for controlling the elliptical travel of the multiple blades and for the simultaneous admission and exit of steam to and from opposite points of the piston, so allowing of an easy and instant reversal of the engine and also of the use of the steam to its maximum expansive value.

In order to clearly understand the construction and operation of this invention, reference will now be made to the accompanying drawings illustrating same, and in which—

Figure 1 is a longitudinal sectional view of the engine. In this figure the continuation of the engine bed-plate and shaft with its outer bearing and wheels is not shown, as such do not constitute essential parts of this invention. Figs. 2 and 3 are transverse sectional views on lines *a b* and *c d* of Fig. 1, respectively. Fig. 4 is a detail elevation of the piston with its blades and ports. Fig. 5 is a section through the exhaust-ports of the piston, as on line *e f* of Fig. 4, while Fig. 6 is a similar view, but

through the steam-inlet ports of the piston, 50 as on line *g h* of Fig. 4.

In the figures, 1 denotes the elliptical-shaped cylinder, formed with the outer steam-jacketed chamber 2. The cylinder by means of its base 3 is secured to the bed-plate 4 of the engine 55 and in the usual manner and is provided with the back and front covers 5 and 6, which are secured by bolts 7 and made steam-tight. The front cover, as 5, is provided or made one with the extension or sleeve piece 8, which acts as 60 a bearing for the engine-shaft 9, and such bearing may be provided with replaceable bushes of antifriction metal or linings, as 10. This shaft is made with the end flange 11, which fits into a recess suitably formed with 65 in the front side of the piston 12 and may be secured by stud-bolts. Said shaft at its outer end is provided with bearings and is of sufficient length to carry a fly or other wheel, as usual. The piston 12 of a diameter equal to the minor 70 axis of the cylinder is circular in shape and made one with the engine-shaft by the flange 11, as above explained, and is thereby arranged and mounted upon such shaft in an overhanging manner. In and across this piston are 75 formed two or more transverse slots 13, which receive and in which are fitted the radially-movable blades 14 of any number and which latter act as the driving agents of the engine. These blades at their ends are formed with 80 trunnions or projections 15, which engage with and work within the continuous grooves or paths 16, formed in the end covers 5 and 6 of the cylinder. These grooves 16 are of an elliptical shape, so as to be agreeable with and 85 concentric to that of the inner curve of their elliptical cylinder, the object of such grooves being to control and cause the working faces of the blades 14 to be kept well home against the inner surface of the cylinder when starting the engine.

A ring, as 17, of an outer diameter equal to the bore of the cylinder is interposed and held between the front cylinder-cover 6 and the side faces of the blades 14, and which ring 95 compensates and takes up the lengthwise wear of the blades as between the covers 5 and 6. This compensation-ring 17 is adjusted by the

screw set-pins 18. Each of these blades is provided with its own steam inlet and outlet passages or ports 19 and 20, respectively, and placed as shown in Fig. 6 such ports extend 5 radially through the piston and communicate with the central steam inlet and outlet passages of the valve, whose end proceeds into and is held within the bore of the piston. This valve formation is circular and longitudinal in form and has its steam-inlet passage 21 placed centrally and constructed as clearly 10 shown in Fig. 1. This passage 21 is made with the oppositely-placed outlet-mouths 22 and which face and lead into the radial steam-ports, as 19, of the piston. The exhaust-passages 23 are formed outside of such central steam - inlet passage and communicate with the outlet-chamber, hereinafter referred to. Said exhaust and inlet passages are 15 formed so as to comprise one piece, as shown in Fig. 1, the inlet-mouths 24 of such exhaust-passages 23 being controlled by a circular sleeve which forms the exhaust-valve, as 25. This exhaust-valve is made with openings 20 which coincide with the outlet-ports of the piston. In the bore of the piston and for its full length is placed a fixed liner-sleeve 26, whose object is to provide a smooth and renewable surface for the exhaust - valve 25. 30 This latter valve proceeds half-way into the piston and rests against the shoulder and also renewable liner-piece 27 and which latter is secured by a stud-point to the steam - inlet valve. This shoulder-piece 27 is formed with 35 openings to coincide with the steam - inlet mouths 22 and with the steam-ports 19 of the piston, and said renewable liner 27 allows of the adjustment of the cross-area of the piston inlet-ports 19. For operative purposes this 40 exhaust - valve is provided at its other end with the toothed rim 28, engaging with its corresponding toothed wheel 29. This latter wheel is mounted on the short shaft 30, held in bearings 31 and provided with gland 32, 45 said shaft being operated by the handle 33, working on and along its notched quadrant 34, as is usual with engine-reversing gear. The steam-inlet gear 21 is placed within the piston and bears on the sleeve 26 and shoulder-piece 27, as shown in Fig. 1. For operating said steam-valve it is at its other end provided with the tooth-rim, as 35, which engages with its wheel 36, mounted on the shaft 37, and said shaft being actuated by the handle 38 and quadrant, as shown, said operative gear being similar in construction and arrangement as that for the steam-inlet valve above described, and such inlet and outlet valves may be independently and simultaneously operated or reversed. The back end of 50 this steam-inlet valve 21 enters the steam-inlet chamber 39, and in order to make a tight joint and obviate any escape of live steam into the exhaust-chamber the necessary packing 55 40 is forced into position by the circular ring

41, and this ring is adjusted by set-pins 42 and retention or lock nuts 43. These pins proceed outward and through the cover 44 of the steam-chamber, as shown in Fig. 1.

The exhaust - steam chest 45 is made one 70 with the back cover 5 of the cylinder or otherwise. The steam-inlet chest is provided with its back cover 46, which is secured by bolts 47, as shown. This back cover is attached or made an integral part with the steam-inlet chamber 39.

The manner of using this invention is mainly as follows: First, let it be assumed that the engine is desired to rotate, as denoted by the index arrow in Figs. 2, 5, and 6. Consequently 80 the handle held in its notched quadrant and the chain of gear, denoted by parts numbered 36 to 38, controlling the steam-inlet valve 21, will all be so placed in fellowship as to cause the mouths 22 of such valve and the openings in 85 the liners 26 and 27 to coincide and face steam-admission passages 19 in the piston, so as to result in the central passage 21 of the steam-valve and the steam-ports 19 in the piston becoming one free and continuous channel for 90 the live steam, as leading from and in communication with the steam-inlet chamber 39, while the exhaust-ports 23 and 24 and 25 are also opened by operating the exhaust-valve gear 29 to 34. The steam being therefore 95 now admitted to its inlet-chamber 39, it proceeds along the passage 21, and thence through the two inlet-steam ports 19 of the piston, and simultaneously enters the cylinder at the opposite points denoted by the steam-arrows 8, 100 Fig. 6. By reason of such entry the blades 14 become subject to the steam-pressure, and consequently the piston is caused to rotate. These blades during such rotation and by means of their trunnions 15 and controlling 105 elliptical grooves 16 are made to move radially outward, so increasing their area upon which the steam acts. After reaching their maximum outward position they recede to their minimum inward position, by which time the 110 live steam has now completed its duty. Concurrent with the cut-off of the live steam the exhaust-ports 20 of the piston are brought over the exhaust-openings 24 of the valve, so allowing for the free escape of the now exhausted steam, as shown by the arrows 115 w, Fig. 5, and through the two outlets 20 of the piston, and thence into the longitudinal exhaust-chambers 23 of the valve, and into the outlet-chambers 45, as shown. Each of the 120 piston-blades individually receive and exhaust two charges of steam during each rotation of the piston. It is obvious that by reason of the rotation of the piston its other steam and exhaust ports, respectively, meet and come 125 opposite the steam-inlets and steam-outlets of their valves, so allowing the steam to enter and exhaust at any point of rotation of the piston in an independent and concurrent manner and as regulated by the valve-oper- 130

ative gears. The peculiar arrangement and construction of the steam inlet and outlet valves with their operative mechanism enables the engine to be started at and from any point 5 of rest and allows of the expansion of the steam being under control and the direction of the engine reversed at will. The exhaust steam, if desired, may be further utilized by compounding the engine by placing two or 10 more engines on the one shaft, each piston working within its own elliptical cylinder and such compounding arrangement being controlled by one or more sets of operative gears. This operation, as described in connection with the two blades, equally applies 15 in respect of all of the other or multiple blades of the piston.

What we claim as our invention, and desire to secure by Letters Patent, is—

20 1. In a reversible rotary engine, the combination with a cylinder, of a rotary piston therein having radially-movable blades, a hollow cylindrical valve on which said piston is mounted, said valve having a central steam-inlet passage and lateral exhaust-passages, and radial steam inlet and exhaust passages in the piston between each pair of blades, substantially as described.

25 2. In a reversible rotary engine, the combination with an elliptical cylinder, of a circular rotary piston therein having radially-movable blades and radial inlet and exhaust passages between each pair of blades, a hollow cylindrical valve having a central steam-inlet passage with oppositely-directed ports 30 and an exhaust-passage on each side of the inlet-passage, a ported sleeve covering the inner ends of the exhaust-passage, means to rotate the sleeve and means to rotate the valve, 40 substantially as described.

35 3. In a reversible rotary engine, the combination with an elliptical cylinder of a circular rotary piston centrally mounted there-

in, radially-movable blades in the piston having lateral trunnions, means engaged by the 45 trunnions to radially move the blades, a central hollow valve having a central steam-passage with oppositely-directed ports at one end and an enlarged steam-entrance at the other, a shorter exhaust-passage on each side of the 50 steam-passage, a rotatable sleeve over the inner ends of the exhaust-passages and means to rotate the valve, said piston having an inlet and an exhaust port between each pair of blades, substantially as described. 55

4. In a reversible rotary engine, the combination with an elliptical cylinder having front and rear covers each provided with an elliptical groove; of a circular rotary piston centrally mounted therein, a shaft having a 60 flange connected to the piston, radially-movable blades in said piston each having a trunnion on its ends, said trunnions moving in the elliptical grooves in the cylinder-covers, a tubular valve extending centrally into the piston and having a central steam-passage with diametrically opposite ports, a shorter exhaust-passage on each side of the steam-passage within the valve, a ported sleeve covering the 65 exhaust-passages, an exhaust-chamber means 70 within the chamber and operated from without the same to rotate the valve, and independent means to rotate the sleeve said piston having a radial inlet and an exhaust-passage to register with the respective ports to 75 the steam and exhaust passages in the valve, substantially as described.

In testimony that we claim the foregoing as our invention we have signed our names in presence of two subscribing witnesses.
